UNITED STATES PATENT OFFICE.

EMMANUEL DE HAAN, OF PARIS, FRANCE, ASSIGNOR TO SOCIÉTÉ BOUCHERON & RADIUS, OF PARIS, FRANCE, A FRENCH CORPORATION.

METHOD OF PIERCING, THREADING, AND ENAMELING TRANSPARENT PRECIOUS STONES.

Application filed September 11, 1924. Serial No. 737,221.

To all whom it may concern:

Be it known that I, EMMANUEL DE HAAN, a citizen of the French Republic, residing at Paris, Department of the Seine, in France, have invented certain new and useful Improvements in the Method of Piercing, Threading, and Enameling Transparent Precious Stones, of which the following is a specification.

10 This invention has for its subject matter an improvement in the method employed for piercing, threading and enameling certain precious stones. For years in order to assemble certain precious stones in the form 15 of collars, necklaces, pendant ear-rings, pendants, etc., it has been necessary to have recourse solely to the means employed for threading pearls which consists either in piercing the stone right through along its 20 diameter or along a symmetrical axis and passing in the passage thus obtained a continuous thread or wire, or in piercing the stone with a single hole of irregular form and of introducing thereinto a metallic wire, 25 thread or the like. This method is quite unsatisfactory from the point of view of beauty when it is a question of transparency the effects of which are due to the reflection and to the refractions of luminous rays 30 which are produced in the mass of the stone. The hole and the thread or wire which passes through the stone along its larger diameter are visible through the material and destroy to a great extent the harmony of 35 these luminous effects, thus rendering it almost impossible to obtain a tiara, necklace or collar of diamonds or other precious stones whilst retaining in the several stones their entire brilliancy and their sparkling effects. 40 The present invention overcomes these inconveniences by reason of the new method of piercing and threading and of enameling. The new method consists in forming one or more than one hole of as small a diameter as possible and as near the edge of the stone 45 as possible. These passages are pierced perpendicular to the adjacent aligned stones. If, for example, it be a question of making a collar of spherical stones the piercing is effected for each stone as near as possible to the periphery of the stone and at two diametrically opposite points. Two adjacent stones are connected by passing a thread, 50 wire or the equivalent through the nearest

holes in the adjacent stones and this thread 55 is knotted or tied or closed in any suitable manner.

The accompanying drawing shows diagrammatically and by way of example constructional forms in accordance with the 60 present invention.

Figure 1, drawn to an enlarged scale, shows partly in section the method of piercing a spherical stone which is to be used for the formation of a necklace. 65

Figure 2 shows the method of assembling several stones so as to form a necklace or collar.

Figure 3 shows another form of assembly in which the stones are suitably pierced. 70

Figure 4 shows the method of piercing a nonspherical stone on the assumption that the stone is to be used for a collar or necklace.

As will be seen from Fig. 1, each stone 75 1 is provided with two holes 2 at opposite ends of the same diameter. The two holes 2 are parallel to each other and perpendicular to the diameter at the end of which they are formed. Into each of these holes is 80 threaded a wire 3, the free ends of which serve to connect the stone to any other stone which is pierced in a similar manner.

The methods of assembly which may be employed are represented in Figure 2. In 85 the left part of this figure, the two lengths of the thread or wire connecting adjacent stones are disposed in an approximately parallel position. In the right hand part of the figure the two lengths of the thread 90 or wire connecting adjacent stones are crossed as indicated at 3'.

In Figure 3 an assembly of stones is shown comprising stones having different orientations. In this case the piercing is effected 95 according to the form of the article of jewelry to which the stones are to be applied. The two stones indicated at the upper part are provided with two holes which are neither parallel nor diametrically opposed. 100 The stone which connects them is provided with three holes, etc. Obviously many other variations in the manner of connecting the stones are possible.

It will be seen from the drawings that the 105 small holes 2 formed adjacent the periphery of the stones cannot have any effect on the brilliancy or sparkling effect of the stone

produced by the special cutting thereof. Further, the mass of the stone is not traversed by a diametrical hole nor by a thread or wire capable of altering the brilliant effects in question.

The method is applicable to transparent stones of all kinds and colours. It is applicable with complete success as stated in the preamble to the present description to stones which are practically of spherical form. More generally it is applicable for the assembly of stones having approximately the form of regular geometrical solids the axis of symmetry of which is disposed in the direction of assembly of the stones. The holes are then pierced adjacent the ends of the axis of symmetry and perpendicular to this axis so that they may be assembled and threaded so as to form a collar, necklace or the like.

Figure 4 shows an example of a cut stone of somewhat olive form intended to be aligned on assembly along its major axis. In order to suitably position the stone it is pierced with two holes 2 at the ends of its major axis and perpendicular thereto. The method may then be used with less interesting advantage for the assembly thereof.

It should be understood that the invention is not limited to the use of any material for

the thread nor to any of the methods shown of assembly, the necklace shown having only been chosen and illustrated by way of example.

Claims:

1. An article of jewelry including a plurality of smoothly cut stones, the bodies of each of which are provided with substantially opposite passageways arranged adjacent the outer edge of the body and parallel to each other and perpendicular of the diameter at which they are provided, and a plurality of links engaged with the adjacent passageways of the adjacent stones for connecting all of the stones together. 40

2. An article of jewelry as claimed in claim 1, wherein the links are formed of wire and include opposed straight portions which are positioned in the passageways so as to prevent relative lateral movement of 50 the several stones.

3. An article of jewelry as claimed in claim 1, wherein the links are formed of wire and include opposed side portions which extend between the stones and are 55 crossed.

In testimony whereof, I hereunto affix my signature.

EMMANUEL DE HAAN.
